UNITED STATES PATENT OFFICE.

ARTHUR E. HUNT, OF NICHOLS, NEW YORK, ASSIGNOR OF ONE-HALF TO
ROBERT C. HARRIS, OF SAME PLACE.

DESIGN FOR A PUMP-BASE.

SPECIFICATION forming part of Design No. 33,005, dated July 24, 1900.

Application filed June 8, 1900. Serial No. 19,629. Term of patent 7 years.

To all whom it may concern:

Be it known that I, ARTHUR E. HUNT, a citizen of the United States, and a resident of Nichols, in the county of Tioga and State of New York, have invented and produced a new 5 and original Design for a Pump-Base, of which the following is a full, clear, and exact description.

Reference is to be had to the accompanying 10 drawings, forming a part of this specification, in which similar characters of reference indicate corresponding parts in all the views.

Figure 1 is a perspective view of a pump-base, showing my design. Fig. 2 is a plan 15 view of the same, and Fig. 3 is a sectional side elevation of the same.

The design in its entirety consists of a hollow body A, from the bottom of which rises a tube B within the body, the tube terminating 20 a distance below the apertured top C of the body, said top C appearing with an annular

depression C', concentric with the top aperture C², and the annular rising wall C³ of the depression being elongated at opposite sides, as is plainly indicated in Figs. 2 and 3, the 25 body appearing approximately bell-shaped, with a flattened side, as at D.

The leading feature of the design consists of the body A, having the apertured recessed top and the rising tube at the bottom. 30

Having thus fully described my invention, I claim as new and desire to secure by Letters Patent—

The design for a pump-base, as herein shown and described. 35

In testimony whereof I have signed my name to this specification in the presence of two subscribing witnesses.

ARTHUR E. HUNT.
